UNITED STATES PATENT OFFICE.

BENJAMIN KAINER, OF NEW YORK, N. Y.

EGG SEPARATOR.

Application filed December 5, 1921. Serial No. 520,031.

To all whom it may concern:

Be it known that I, BENJAMIN KAINER (name changed by order of court from BENJAMIN KAISER), a citizen of the United States, and a resident of the city, county, and State of New York, have invented certain new and useful Improvements in Egg Separators, of which the following is a specification.

10 My invention relates to crates for packing eggs for shipment, handling and storage purposes, and it relates more especially to the separators for holding the eggs in separated relation in the crate. The object of my invention is to provide a very simple and efficient separator for eggs which can be made very cheaply and the one herein illustrated can be made approximately as cheaply as the ordinary cardboard separator most commonly used for such purposes. In fact, the increased cost of manufacture is almost negligible as it simply requires a slight additional quantity of stock.

In the shipment of eggs from the producers to the markets and even in shipping between points in the same city there is always a large percentage of breakage and this has been a great economic waste. Many attempts have been made to provide separators which would reduce the breakage. Most devices heretofore tried and which gave even partially successful results have been expensive to make and as the original cases and separators are not generally returned to the shippers the additional cost of such separators has prevented their adoption for general use. This for the reason that the additional cost of the separators to the original shippers offset the saving in breakage of the eggs. The present device is adapted to prevent breakage and not add materially to the cost of the ordinary separator.

An egg resists breakage more strongly in the direction of its length or major axis but the way they are now most commonly packed for shipment they receive most of the shocks during shipment in the direction of their minor axis in which direction they are less able to resist breakage. In the present device the eggs are retained with their major axes vertical in the case to prevent or reduce breakage. The device may be made with compartments of uniform size but the flap used to retain the eggs in proper position adjusts itself to eggs of different sizes and maintains them in the position referred to.

In addition to the springiness of the top and bottom walls with which the eggs engage, the present device forms a spring support at the sides which will nevertheless retain the 60 eggs in the correct position in the case. The eggs may be packed in the present device as rapidly as in the standard crates now in use.

In the drawing forming part of this application,

Figure 1, is a perspective view of a portion of one of my improved separators,

Figure 2 is a sectional view thereof showing the eggs packed therein,

Figure 3 is a face view of one of the strips 70 of which the separator is formed, and

Figure 4 is a face view of one of the strips which runs at right angles thereto.

I prefer to make the separator of the collapsible type conforming to present practice 75 because they can be shipped in flat condition to the users; although my invention is not limited to a collapsible type. Herein I have shown a series of strips 1 of cardboard which may extend lengthwise of the case or 80 container 2; and a series of cardboard strips 3 which may extend crosswise of the case or at right angles to the strips 1. The strips 3 are provided with slots 4 in their upper edges and with T shaped apertures 5 lower 85 down or nearer the bottom edge, these slots and apertures being repeated along the strips equal distances corresponding with one dimension of the egg compartments. The strips 1 are each provided with slots 6 90 along their bottom edges, which slots are so shaped as to provide tongues 7. When the strips 1 are placed over the strips 3 and at right angles thereto with the slots 6 in line with the strips 3 and with the strips 1 in line 95 with the slots 4, the strips 1 may be moved down until the strips are in the same plane and then the tongues 7 snap into the T shaped slots 5 as shown in Figure 1 and lock the longitudinal and cross strips together. 100 Any number of strips are assembled in this manner to provide a separator of such dimensions as to conform to any size case or container. The separator may be collapsed, the strips 1 pivoting on the strips 3 so that 105 the separators may be shipped to the users in flat condition.

Thus far I have described an ordinary form of separator and it is to be understood that any other form of lock for engaging 110 the strips 1 and 3 may be used so far as my present invention is concerned.

The separator forms compartments 8 or rather they form the four walls of a number of such compartments. In addition to the above I provide a flap 9 for each compartment 8. In the preferred construction, the flaps 9 are formed as continuations or extensions at the top edges 10 of the strips 1 and therefore these strips may be blanked out by machinery with the flaps 9 forming integral parts thereof. It is unnecessary to form any crease line where the flaps 9 join the strips 1 as the flaps 9 may be bent over when the separators are put into use, and the resistance to the bending of the stock 15 serves as a force to hold the flaps against the eggs.

Flat sheets 11 for bottoms and tops for the several compartments 8 are used as in present practice. In using the separators 20 the shipper packs the case in a manner very similar to what has been common practice. Generally, a layer of corrugated board (not shown) is placed in the bottom of the case for the bottom layer of eggs to rest on and 25 then one of the separators is placed on this corrugated board; an egg is placed in each compartment 8 of the separator and then a top sheet 11 is placed on the first separator. Then another separator is placed on this top 30 sheet, eggs are placed in its compartments and another top sheet is placed thereon; and this is repeated until the whole crate has been packed.

The separator is placed in the crate with 35 the flaps 9 at the top of the separator and as the packer is about to place an egg in each compartment 8 he first bends down the flaps 9 to force it down into the compartment 8 and then he places the egg in the compartment with its major axis vertical. The egg rests against the wall 12 of the compartment 8 and on the opposite side it is engaged by the flap 9 and is held by it pressed against the wall 12. The flap 9 prevents the egg

from turning over in the compartment so 45 that it lies in the case with its major axis vertical. In this position the egg resists breakage to a greater extent than it otherwise would. Since the egg is prevented from shaking around in the compartment the liability of breakage is reduced to a minimum. One egg is placed in each compartment in the manner described and when the separator is filled a sheet 11 is placed upon it and then another separator is placed upon the 50 sheet; and this procedure is followed until the whole crate has been filled.

It will be apparent that the only additional cost of the present article over separators now in general use is the cost of the 55 stock of which the flaps 9 are composed, which is almost negligible. The separators may be filled about as rapidly as in present practice.

Having described my invention what I 60 claim is:—

1. A separator for holding eggs in a crate comprising a plurality of longitudinal and cross strips forming compartments between them to receive therein the eggs for shipment, and flaps extending from the top edges of said strips and into said compartments and adapted to press the eggs into contact with the walls of said compartments. 70

2. A separator for holding eggs in a crate 75 comprising a plurality of longitudinal strips, a plurality of transverse strips interlocking therewith to form the walls of compartments, and adapted to be collapsed into flat form, integral flaps extending from the 80 edges of some of said strips and having free ends projecting into said compartments, said strips being adapted to press the eggs into contact with the walls of said compartments to retain the eggs vertically therein. 85

Signed at the city, county and State of New York, this 12th day of November, 1921.

BENJAMIN KAINER.
